UNITED STATES PATENT OFFICE.

ENOS C. POLLARD, OF SEATTLE, WASHINGTON.

SMELTING AND REFINING APPARATUS.

No. 813,825.

Specification of Letters Patent.

Patented Feb. 27, 1906.

Application filed April 25, 1905. Serial No. 257,295.

To all whom it may concern:

Be it known that I, ENOS C. POLLARD, a citizen of the United States, and a resident of Seattle, in the county of King and State of Washington, have invented a new and Improved Smelting and Refining Apparatus, of which the following is a full, clear and exact description.

This invention relates to an apparatus for the direct conversion of ores and mattes into metallic product—that is to say, an apparatus in which the smelting of the ore and the refining of the matte is carried on in one continuous operation.

15 The invention is especially designed for use in connection with copper ores and mattes, although, of course, its use is not limited to connection with these substances.

Generally described, the apparatus comprises a converter, above which is arranged a cupola-furnace, the lower end of which is constructed with a sort of boot or bowl-like portion, into which the throat of the converter opens. From the lower portion or boot of the cupola a passage extends to a forehearth or settler located directly adjacent to the cupola-furnace and having also a passage leading into the converter, said passage being at a greater elevation than the lower end of the passage from the cupola-furnace. At the bottom of the converter is located a base or box for receiving the refined product, and this box or base communicates with a receptacle, into which said refined product is discharged.

35 By means of this apparatus I am enabled to keep up a continuous smelting and refining operation. The matte and slag produced in the cupola-furnace flows through the passage therefrom into the settler. From this settler the lighter and less valuable portions of the slag pass off to the dump, while the matte and more valuable portions of the slag pass by gravity into the converter. Here the matte is subjected to a Bessemerizing blast, and the slag is forced back into the bowl or boot of the cupola-furnace, thus bathing the matte and other substances therein and returning to the settler in the 45 manner before described. The refined metal passes from the base or box of the converter out into the receiver and is drawn therefrom as it accumulates.

This apparatus is especially useful for the performance of the process for the direct conversion of copper ores and mattes into metallic copper, which forms the subject-matter of my copending application, Serial No. 209,091, filed May 21, 1904, and it contains matter originally disclosed and claimed in said copending application and divided therefrom in compliance with an official requirement.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a vertical section on the line 1 1 of Fig. 2 of a preferred form of my apparatus, showing elements in the rear in section on the line 3 3 of Fig. 2. Fig. 2 is a vertical section on the line 2 2 of Fig. 1. Fig. 3 is a sectional view, on an enlarged scale, of certain details on the line 3 3 of Fig. 2; and Fig. 4 is a sectional view on the line 4 4 of Fig. 3.

F indicates the cupola-furnace; C, the converter, and B the box or base thereof.

S indicates the settler or forehearth, and R indicates the receiver for the refined copper or other metal. These parts are supported on a suitable framing, which will not be specifically described, since in itself it forms no part of my invention.

F' indicates the boot or bowl at the bottom of the cupola-furnace, and into this the throat of the converter empties.

Reference to Fig. 2 will show that the furnace and converter are transversely elongated, which arrangement I consider best in practice, although it is not essential. From the bottom portion or boot F' of the furnace a passage P extends, this passage running downward and discharging into the bottom of the settler. A second passage P' passes from the settler at a point above the discharge or lower end of the passage P, this passage P' discharging into the lower part of the converter. A passage P² extends from the bottom of the box or base B into the receiver R.

The box or base B is supported on jacks 10 and comprises an outer shell 11, of metal, deeply lined with clay or other non-conduct-

ing material 12, preferably faced with magnesite. It is preferably supplemented by a thin shell 13, of basic material, in the shape of an inverted arch of magnesite brick. 14 indicates the bustle-pipes for supplying the blast to the twyters 15 of the converter.

The settler 3 is preferably supported on casters 24 and is constructed of a metallic shell 25 at its bottom and inner and outer shells at its sides, forming a water-jacket. The settler is lined with brick 27 or the like and provided with a lid comprising a metallic shell 28 and a brick lining 29.

30 indicates a vertical slot formed in the settler for drawing off the slag, and in this slot is placed a vertically-adjustable dam-plate 31, provided with an orifice 32. By raising and lowering this plate the level at which the slag is allowed to accumulate in the settler may be regulated, it being understood that when the slag reaches the level of the orifice 32 it passes off to the dump.

33 indicates a tap for drawing off the heavier portions of the matte which accumulate in the settler and which lie too low to be passed into the converter through the passage P'. The passages P² and P' are formed of inner and outer shells not only constituting the passages, but also forming water-jackets for cooling the same.

The parts so far described are all represented in the above-mentioned application. Some of them, however, are shown in an improved form in the present case.

35 The hood 40, which covers the converter, is separated therefrom at the top of the non-conducting material in the box or casing 11; but a free passage is provided through it from the converter for the heated gases and products of combustion to pass into the furnace F. As this hood serves merely for this purpose, it may be built of any desired fireproof material.

The bustle-pipes 14 are constructed in the form of hollow iron pipes extending along the interior walls of the converter and, in fact, forming the interior surface of the walls. The passage of the air through these hollow walls cools them and prevents their destruction by the molten slag in the converter.

45 The blast passes from these pipes through pipes 41 into the inclined shafts 15, which I have designated as "twyters." These shafts simply passages molded in the lining and extending upward and outwardly from the pipes 41 by iron pipes 42, closed at the ends by caps 43, screwed onto the pipes to form air-tight joints. These caps may be removed for the purpose of attending to any obstruction at the foot of the shaft or elsewhere within reach. While I have called these shafts "twyters" and it is to be understood that they have the same purpose as twyters, it will be seen that they are entirely different

from what is now known in the art as "twyters" 65 as far as construction is concerned.

In the use of a converter constructed as above described the pressure of the blast prevents the rise of the matte in these shafts, and the air from them instead of being projected from their ends escapes under water-cooled pipes 44, located at the mouths of the shafts, and rises vertically through the matte and supernatant layer of slag.

70 The slag may be drawn from the converter by kinetic energy due to the blast through the twyters and the dynamic energy of effervescence due to the production of sulfur dioxid, which is formed from the reaction between the cuprous oxid and cuprous sulfid present in the matte. The sulfur dioxid formed escapes in minute bubbles, causing the slag to increase in volume to form and occupy greater space, and hence to be specifically lighter than the same slag prior to forming.

75 This action, together, as has been said, with the moving force of the blast, causes the slag to rise, so that it can be withdrawn; but I prefer to provide an additional means for accomplishing this result, as it is desirable to raise the slag sufficiently high to allow its being introduced into the furnace above the zone of fusion, whereby the danger of a silicious skeleton being left in the furnace after the sulfids have been liquefied is avoided.

80 In the form shown the slag is drawn from the converter through a passage P². This passage is formed in a wall 45, which separates the receiver R from the converter, of which it is an extension.

85 It is inclined downwardly, so as to readily discharge the slag into the bottom of a stand-pipe 46. This stand-pipe is provided with a water-jacket 47, and its upper end is connected, by means of a downwardly-inclined portion 48, with a pipe 49, the water-jacket covering all of these portions. The pipe 49 is provided with conductors 50, by means of which the slag is discharged into the furnace on the top of the ore and other materials which may be therein, ready for fusion or in the act of being fused. A passage 51 is also provided for the purpose of draining the pipe 49, and it is ordinarily closed, so as to force the slag to pass into the furnace through the pipe 50.

90 The passage 51 is continued through the pipe 49 and is extended upon the outside thereof by means of a pipe 52, which can be closed by a cap 53. This construction is provided so that a bar or the like may be introduced to open the passage 51.

95 A pipe 54 is also provided for draining the stand-pipe and the passage P². The wall 55 of the furnace below the outlet of the passage 50 is preferably vertical, while the opposite wall 56 is battered, and the same wall above the outlet 50 is also battered

100 to form a bosh. The melting-furnace is preferably provided with twyters 57, as usual.

The passage P and pipe 46 constitute means for establishing a circulation of materials between the furnace and converter.

In order to provide for forcing the slag up through the stand-pipe 46 and into the furnace F, the bottom of the stand-pipe is provided with a conical tube 58, having its larger diameter at the top. The top of this tube is open to admit slag from the stand-pipe and is 5 preferably located at a lower level than the top of the passage P³. At the bottom of this conical pipe is located a shell 59, having two annular passages 60 and 61, one located above the other and not normally communicating 10 with each other except through an opening 62, which is ordinarily closed by means of a valve 63. This valve also closes the bottom of the conical pipe. A nut 64 is mounted below the valve and is adapted to be removably 15 screwed into position, so that it will press upon a spring 65 and force the valve to its seats. The nut may be removed for cleaning purposes. The valve is designed to be operated to open and allow communication 20 through both of the passages which it closes when the pressure of the gases above it is sufficient to overcome the resistance of the spring 65. This permits air introduced into 25 the passage 60 through a conductor 66 and an explosive gas or mixture introduced into the passage 61 through a conductor 67 to mix 30 and flow into the bottom of the conical pipe 58. This mixture being heated by the slag in the pipe explodes and furnishes the motive power for raising the slag in the stand-pipe. The air and explosive mixture are 35 preferably at the same pressure in the annular passages, and that pressure should be greater than the pressure of the column of slag above. 40 As the explosions take place in the tube 58, I shall hereinafter designate this element as the "explosion-tube."

The connection between the two annular passages in the shell 59 is preferably formed 45 by a plurality of small ports which provide for the intimate mixing of the gases when they are introduced into the explosion-tube. A portion of this tube is inclosed in a water-jacket 68, divided into two parts by a vertical dam 69, extending almost to the top of 50 the jacket. Water is admitted into the jacket on one side of the dam and flowing upward over it escapes at the bottom on the other side. A portion of the tube extends above 55 the water-jacket, so that it may become heated, and thus explode the gas before the level of the slag has risen entirely above the tube. After rising through the stand-pipe 46 the 60 gases escape through an exhaust-pipe 70 to the stack. By this method of drawing the slag from the converter the flow may be regulated at will by simply increasing or decreasing the supply of explosive mixture. The slag may also be raised sufficiently high to ad-

mit of its being poured onto the upper surface of the ore in the furnace, where its scouring action on the charge can be utilized throughout the entire mass of ore as it sinks regularly and rapidly in the furnace.

In operation the ore, with the proper admixture of flux, is fused in the furnace F to produce a matte in the boot f, and this, with the resultant slag, is drawn off and allowed to settle in the settler S. The lighter and relatively valueless portions of the slag are then 70 run off to the dump through the passage 32, which is adjusted as described above, so that it will discharge only that slag which contains less than a certain percentage of copper. After this the matte and remaining slag are 80 subjected to the action of blasts of air to Bessermere the matte, producing a finished metallic product which is allowed to run into the receiver R and forcing the metals oxidized by the blasts into the slag. The supernatant layer of slag, which receives the oxids, is allowed to flow through the passage P³ into the stand-pipe 46, and by the proper regulation of the conductors 66 and 67 the gas-pressure in the stand-pipe will cause the valve 90 63 to open and the proper explosions to take place in order to conduct the slag into the furnace F, where it bathes the matte and the silicious component of the ore to absorb a portion thereof and passes off therewith to be 95 settled again. It will be noticed that by introducing the slag at this point it flows by gravity through the ore and through the settler back into the converter, and thereby better serves its purpose as a carrier of ferrous oxid to the silica and of silica to the ferrous oxid. After once starting the process is continued cyclically, the slag and matte being kept in steady movement so long as operations are to be performed thereon, 100 the ore being continually charged into the melting-furnace, the lighter portions of the slag being steadily drawn off to the dump and the refined or finished metallic product being drawn out when the proper degree of 105 refinement is obtained.

The arrangement of the blast-conducting devices in the converter is an important feature of the invention. The advantages of this are many. First, it renders it unnecessary to cool the converter by water except by the small pipes 44, as the air of the blast absorbs heat from the lining and returns it again to the contents of the converter. Although being already heated to some extent, it will absorb less heat than would cold air. Second, 115 the blast escaping in a continuous sheet from the lower ends of the passages 15 throughout the full length of the converter, it is possible to use much more air and still consume all its oxygen than would be possible where the air must be blown through twyers with comparatively narrow outlets. Moreover, a 120 125

much lower pressure is necessary, because where the air is blown through twyters it must have sufficient force to be projected into the molten mass a few inches beyond the 5 ends of the twyters before rising vertically. By the arrangement here shown the air is not released until it is in the interior of the converter so far from the walls that in rising there will always be matte on either side of it, 10 and the pressure needed is merely enough to balance the pressure of the matte plus that of the slag and the back pressure of the escaping gases. The blast can be given no greater pressure than this, as with any increase it will merely escape more rapidly. The additional force required, therefore, to compel the air to rise at a point away from the walls of the converter is saved, because the gases pass around the pipes 44 and up 15 through the converter from the opening in the inclined bottom thereof. This is a great saving, as the expense of the blast is the principal item in the cost of treatment by this process, and the cost of compressing air is 20 proportional to its final pressure. In addition to this this construction prevents the annoyance due to copper noses forming over the twyters and renders it possible to suspend operations for a considerable period without 25 danger. A ball-valve 71 in the bustle-pipe prevents the backward flow of the compressed air, and hence the rising of the matte, in the shafts or inclined passages 15, and even if this air should escape the matte 30 merely rises in the shafts, which are purposely made so large as to permit this without danger of their becoming filled with solid copper for a considerable period. The water-pipes 44 become covered with a chill of 35 matte, and as the surface exposed to the cooling influence of the water remains constant, while the surface exposed to the heat of the molten matte increases with the depth of the chill, there must necessarily be a point 40 in the thickness of this chill where the heat, abstracted by the water, balances that absorbed from the matte, and this will occur in a few inches. The blast sweeping over the surface of the matte beneath the water-pipe 44 becomes highly heated before escaping 45 upward, and in coming into contact with the low-grade matte its oxygen attacks the sulfur and iron with greater avidity than would be the case were the blast cold. 50

Having thus described my invention, I claim as new and desire to secure by Letters Patent—

1. The combination of a furnace having a boot or bowl-like portion at its lower end, a 55 converter having a throat opening into the lower part of the furnace, a settler, and means for conducting molten materials from the boot of the furnace into the settler and from the settler into the converter.

2. The combination of a furnace having a boot or bowl-like portion at its lower end, a converter having a throat opening into the lower part of the furnace, a settler, means for conducting molten materials from the boot of the furnace into the settler and from the settler into the converter, and a receiver in communication with the converter to receive finished product therefrom.

3. The combination of a converter, a melting-furnace, means for establishing a cyclical 75 passage of molten materials from the converter to the furnace and from the furnace to the converter, and a receiver in communication with the converter to receive finished product therefrom.

4. The combination of a converter, a melting-furnace, and means for causing molten material to flow from the converter to a point in the furnace at a higher level than the converter, discharge said materials onto the 85 contents of the furnace, and cause a transfer of materials from the interior of the furnace into the converter.

5. The combination of a converter, a melting-furnace, means for establishing a passage 90 of molten materials from the converter to the furnace and from the furnace to the converter, and a settler or forehearth located in and forming part of the path of the molten materials.

6. The combination of a converter, a melting-furnace, means for conducting material from the furnace to the converter, and separate means for conducting materials from the converter to the furnace.

7. The combination of a furnace having a depressed lower portion, a converter located at a lower level than the bottom of the furnace, said converter having a hood communicating with its top and with the furnace, 105 means for conducting materials from the lower part of the furnace into the converter, and means for conducting materials from the converter into the upper part of the furnace.

8. The combination of a furnace, a converter located at a lower level than the bottom of the furnace, means for conducting material from the lower part of the furnace into the converter, and means for conducting material from the converter into the upper part 115 of the furnace.

9. The combination of a furnace, a converter, means for conducting material from the lower part of the furnace into the converter, and means for conducting material 120 from the converter into the upper part of the furnace.

10. The combination of a converter, a melting-furnace, means for conducting material from the furnace to the converter, and 125 separate means for conducting materials from the converter to the furnace; said separate means comprising a conductor discharging

ing into the furnace, and means in the conductor for forcing material therein to ascend.

11. The combination of a converter, a melting-furnace, means for conducting material from the furnace to the converter, and separate means for conducting materials from the converter to the furnace, said separate means comprising a conductor discharging into the furnace and means in the conductor for forcing material therein to ascend; said last-named means comprising an explosion-tube and means for conducting a mixture of explosive gases into said tube.

12. The combination of a converter, a melting-furnace, means for conducting material from the furnace to the converter, and separate means for conducting materials from the converter to the furnace; said separate means comprising a conductor discharging into the furnace, and means in the conductor for forcing material therein to ascend; said last-named means comprising a conical explosion-tube having an open upper end and a passage in its lower end, a valve for closing said passage, a pair of chambers normally separated from each other, said valve controlling communication between said chambers, and yielding means for normally forcing the valve to close communication between said chambers and also to close the opening in the bottom of the explosion-tube.

13. The combination of a melting-furnace, a converter located at a lower level than the melting-furnace and having a discharge-opening adapted to deliver slag by gravity from the converter, a stand-pipe communicating with the lower end of said discharge-opening and extending to a point above the bottom of the furnace, a pipe for conducting material from the stand-pipe to the furnace above the charging-line thereof, and means for causing materials in the stand-pipe to ascend therein and be discharged into the furnace.

14. The combination of a melting-furnace, a converter having a discharge-opening adapted to deliver slag from the converter, a stand-pipe communicating with said discharge-opening and extending to a point above the bottom of the furnace, a pipe for conducting material from the stand-pipe to the furnace, and means for causing material in the stand-pipe to ascend therein and be discharged into the furnace.

15. The combination of a converter, a conductor for conveying materials therefrom, and means in the conductor for forcing material therein to ascend; said last-named means comprising a conical explosion-tube having an open upper end and a passage in its lower end, a valve for closing said passage, a pair of chambers normally separated from each other, said valve controlling communication between said chambers, and yielding means

for normally forcing the valve to close communication between said chambers and also to close the opening in the bottom of the explosion-tube.

16. The combination of a converter, a melting-furnace, and means for conducting material from the converter to the furnace, comprising a conductor, an explosion-tube in the conductor for forcing material therein to ascend, and means for conducting a mixture of explosive gases into said tube.

17. The combination of a furnace having a depressed lower portion, a converter located at a lower level than the bottom of the furnace, said converter having a hood communicating with its top and with the furnace, means for conducting materials from the lower part of the furnace into the converter, and means for conducting materials from the converter into the upper part of the furnace; said converter having passages in its walls constituting twyers, and opening near the bottom of the converter.

18. The combination of a converter having passages molded in its walls and opening at the bottom thereof, said passages constituting twyers, means for conducting compressed air to said passages, a melting-furnace, means for conducting molten materials from the melting-furnace to the converter, and means for conducting molten materials from the converter to the melting-furnace.

19. The combination of a converter having a molded lining, and a pipe constituting a portion of the inner wall of the lining, a passage in the lining constituting a twyer and passages for conducting air from the pipe to the twyer, and means for conducting molten material from the converter.

20. The combination of a converter, said converter being provided with inclined passages in its walls upon opposite sides thereof and converging toward the bottom of the converter, bustle-pipes also in its walls and constituting part of the inner face thereof, passages from the bustle-pipes to the inclined passages, and water-cooling pipes located above the mouths of the inclined passages within the converter, and means for conducting molten materials from the converter.

21. The combination of a converter, a furnace into which the converter discharges, a settler, means for conducting molten material from the furnace to the settler and from the settler to the converter, a vertically-adjustable overflow-conductor in the settler, and a receiver in communication with the lower part of the converter to receive the finished product thereof.

22. The combination of a converter, a furnace into which the converter discharges, a settler, means for conducting molten materials from the furnace to the settler and from the settler to the converter, a vertically-ad-

justable overflow-conductor in the settler, and a receiver in communication with the lower part of the converter to receive the finished product thereof; said receiver constituting a portion of the converter and being separated therefrom by a non-conducting partition.

In testimony whereof I have signed my name to this specification in the presence of two subscribing witnesses.
